UNITED STATES PATENT OFFICE.

EDWARD T. NEWLIN, OF BROOKLYN, NEW YORK.

COFFEE-POT.

SPECIFICATION forming part of Letters Patent No. 399,431, dated March 12, 1889.

Application filed December 30, 1887. Serial No. 259,400. (No model.)

To all whom it may concern:

Be it known that I, EDWARD T. NEWLIN, of Brooklyn, in the county of Kings and State of New York, have invented a new and Improved Coffee-Pot, of which the following is a full, clear, and exact description.

The object of this invention is to improve the construction of coffee-pots of the class in which an infusion is obtained by passing water through the ground coffee, which is held in a fabric strainer near the top of the coffee-pot.

The invention consists in a compressible ring held in the margin of the strainer, in a removable support for the strainer, and in details of construction and combinations of parts, as will be hereinafter more specifically set forth and claimed.

Reference is to be had to the accompanying drawings, forming a part of this specification, in which similar letters of reference indicate corresponding parts in all the views.

Figure 1 is a central sectional elevation of a coffee-pot having my invention applied. Fig. 2 is a plan view with the strainer removed, and Fig. 3 is a partly sectional plan view of the compressible ring.

Within a hem or shirr, *a*, formed in the upper marginal edge of the fabric strainer *A*, is held loosely a compressible ring, *B*, formed in the present instance from a piece of spring-metal tubing of small diameter, bent into ring form, and having secured in one end, preferably by soldering, a short piece of wire, *b*, which projects therefrom and is adapted to enter the other end of the bent tube, whereby, by pressure applied to the periphery of the ring, the same can be reduced in diameter, so as to be passed into the contracted top of an ordinary cone-shaped coffee-pot and removed therefrom with ease when required.

A tripod-shaped spring-wire frame, *C*, having the ends of its arms *c* bent inward to form the projections *d*, is inserted in the coffee-pot, with its shank *e* resting on the coffee-pot

bottom, so that when the strainer is placed in the coffee-pot the ring *B* will rest on the projections *d*, and the strainer will be securely upheld.

A socket, *D*, is secured centrally on the bottom of the coffee-pot, in which socket the end of the shank *e* of the tripod *C* can be inserted to hold the same firmly in place; but this socket is not essential, as the tripod, ring, and strainer will be sufficiently well sustained by the spring-tension of the arms *c* and ring *B* when the same are applied to a coffee-pot not provided with the socket *D*.

The ring *B* may be otherwise made compressible without departing from the spirit of my invention; but the form shown is at present preferred as presenting no ends to puncture the fabric of the strainer, and a strainer provided with a compressible ring may be otherwise held in position in the pot.

Having thus fully described my invention, I claim as new and desire to secure by Letters Patent—

1. In a pot, the combination, with a spring-tripod and a strainer, of an elastic split ring having a segmental piece of smaller diameter rigidly secured in one of its ends, and a tubular opening in its opposite end, in which said piece is placed and is adapted to work, substantially as described.

2. In a coffee-pot, a strainer-support consisting in a tripod formed of a series of elastic arms converging and united at their lower ends, free at their upper ends, and bowed outwardly between their ends, substantially as set forth.

3. The combination, with a coffee-pot provided with a socket on its bottom, of a spring-tripod adapted to fit into said socket, and a strainer sustained on said tripod, substantially as set forth.

EDWARD T. NEWLIN.
